AUTOMOBILE TAIL LAMP

Clifford C. Voss, Clawson, and John E. Schwarz, Oak Park, Mich., assignors to Chrysler Corporation, Highland Park, Mich., a corporation of Delaware

Application July 29, 1957, Serial No. 47,127

Term of patent 7 years

(Cl. D48—32)

Fig. 1 is a side elevational view of an automobile tail lamp showing our new design;

Fig. 2 is a front elevational view of the automobile tail lamp of Fig. 1;

Fig. 3 is a sectional view taken on the line 3—3 of Fig. 2; and

Fig. 4 is a sectional view taken on the line 4—4 of Fig. 1.

We claim:

The ornamental design for an automobile tail lamp, substantially as shown.
